United States Patent Office.

F. B. MORSE, OF PLANTSVILLE, CONNECTICUT, ASSIGNOR TO HIMSELF AND
H. D. SMITH & CO., OF SAME PLACE.

Letters Patent No. 96,252, dated October 26, 1869.

IMPROVEMENT IN CARRIAGE-CLIPS.

The Schedule referred to in these Letters Patent and making part of the same.

To all whom it may concern:

Be it known that I, F. B. Morse, of Plantsville, in the county of Hartford, and State of Connecticut, have invented a new Improvement in Spring-Bar Clip for Carriages; and I do hereby declare the following, when taken in connection with the accompanying drawings, and the letters of reference marked thereon, to be a full, clear, and exact description of the same, and which said drawings constitute part of this specification, and represent in—

Figure 1, an edge view;

Figure 2, a side view of the clip complete as an article of manufacture;

Figure 3, a section on line *x x*;

Figure 4, a section on line *y y*;

Figure 5, the blank preparatory to the formation of the clip; and in

Figure 6, a top view as it comes from the dies.

This invention relates to an improvement in spring-bar clips for carriages, that is to say, clips which are used to secure the spring of the carriage to the spring-bar.

Heretofore these articles have been formed by upsetting the metal from either end.

The object of my invention is to facilitate the manufacture of these clips by forming them so that they may be struck up in a single die. To this end,

The invention consists in forming the clip from a round rod, the diameter of the rod being that required for the screw or bolt-ends, and of a length the same as the length of the clip when complete from end to end; then in dies suitably formed, so that when the said round rod is heated and placed therein it is struck into form, flat upon its under side, and moulded upon its upper side, the widest at the centre, and tapering

toward the base of the screw or bolt-ends, and the same quantity of metal at all points from end to end.

To enable others skilled in the art to make and use my invention, I will proceed to describe the same, as illustrated in the accompanying drawings.

A, in fig. 5, is the blank, being a round rod of the diameter required for the bolt-ends B B, when complete.

This rod is heated to the required heat, then placed in dies formed for the purpose, and struck into shape, as seen in fig. 6, the two ends preserving their original shape for the bolts, and between the two bolts B B the metal is spread and moulded, as seen in figs. 3 and 4, being thinner and broader at the centre, narrowing toward each end, yet retaining the same amount of metal from end to end.

Thus the clip, while it is strengthened laterally at the base of the bolt where such strength is required, and brought into ornamental shape, is not upset, that part of the process being saved and a better and more ornamental clip produced at a single operation than has heretofore been done by a combination of several operations.

The clip, as an article of manufacture, is not threaded at the bolt-ends, this being left for the consumer.

Having fully described my invention,

What I claim as new and useful, and desire to secure by Letters Patent, is—

Carriage-clips, as an article of manufacture, constructed and formed substantially as herein described.

F. B. MORSE.
